PAPER-FEEDING DEVICE.

1,122,792.

Specification of Letters Patent.

Patented Dec. 29, 1914.

Application filed July 21, 1909. Serial No. 508,733.

To all whom it may concern:

Be it known that I, SAMUEL A. NEIDICH, of Burlington, in the State of New Jersey, have invented a certain new and useful Improvement in Paper-Feeding Devices, whereof the following is a specification, reference being had to the accompanying drawings.

My invention may be advantageously employed to feed cut sheets of paper or other flexible fabric to a printing machine, and particularly to what is known as a duplicating machine wherein the sheets are received in a substantially horizontal plane.

My invention is arranged to successively feed sheets singly from the bottom of a stack of sheets by first pushing back the forward edge of the bottom sheet so as to disengage it from its normal support and then directing said edge between rollers adapted to withdraw the sheet from the stack by their rotation.

In the form of my invention hereinafter described a series of frictional feed rollers is arranged for continuous rotation and a series of projecting fingers is arranged to be intermittently rotated beneath the stack of sheets supported in such a manner as to be normally upheld free from said rollers, but arranged to be engaged at predetermined intervals by said fingers; such engagement effecting the backward movement of the forward end of the bottom sheet to disengage it from the stack supporting means and permit it to be gripped and progressed between said friction feed rollers and another subjacent series of feed rollers, co-operating therewith. As hereinafter described, the means for intermittently shifting said fingers includes a crank arm rigidly secured to the shaft carrying said fingers, arranged to be engaged and positively shifted when said fingers contact with said bottom sheet, by a pin on an independently driven gear loosely mounted on said shaft. Said fingers are shifted out of engagement with said sheet after drawing back the forward edge of said sheet, by the friction of the upper feed rollers which are rotated at an accelerated rate of speed on said shaft, by engagement with said subjacent feed rollers.

My invention includes the various novel features of construction and arrangement hereinafter more definitely specified.

In the drawings, Figure I is a plan view of a paper feeding device conveniently embodying my invention. Fig. II is a side elevation of said device. Fig. III is a vertical longitudinal sectional view of said device taken on the line III, III, in Fig. I. Fig. IV is a fragmentary elevation of the outer end crossbar of the frame of said device indicated at the left hand side of the other figures.

In said figures, the frame comprises the side plates 1, and 2, which are rigidly connected by the outer end cross bar 3, by the intermediate bolt rods 4, by the inner end holder plate 5, and the chute including the horizontal plate 6, and the inclined upper plate 7; said chute serving to direct the sheets 9, in their successive discharge from the stack 11 to the printing machine. Said frame may be attached to the printing machine or to any suitable support by screws fitted in the sockets 12 in said side plates as indicated in Figs. II and III. As indicated in Figs. I and III said stack 11 is supported by the parallel idle rollers 13 extending between said frame plates 1 and 2, being journaled upon the center screws 14, and 15, which are respectively fitted in the frames 1, and 2, and have the reduced inner ends extending into the socketed ends of said rollers, as indicated in dotted lines in Fig. I. Said stack 11 is held on said rollers against the stationary holder plate 5, and maintained in alinement by the lateral holder plates 16, and end holder plate 17. Said plates 16 are respectively supported in connection with said frame plates 2 by the rods 19, which are coupled at their outer ends by the yokes 20, and held in adjusted position by the set screws 21. Said holder plate 17 is supported in connection with said cross bar 3 by the rods 23 connected by the yoke 24, and held in adjusted position by the set screws 25. The bearings for the rods 23 extend in the cross bar 3 and said rods are maintained therein by the removable blocks 26 which as shown in Fig. III are bolted beneath said cross bar 3. This construction also provides bearings 27 in registry with the screw threaded openings 28, to which said set screws 25 may be removed to engage another end holder plate similar to the plate 17 but of greater width and having supporting rods similar to the rods 23, but in such spaced relation as to fit the

105
110

bearings 27. As shown in Fig. III, the outer ends of the sheets 9 in the stack 11 are upheld by the horizontal flange 29 on said holder plate 17, the inner ends of said sheets 9 being upheld by the horizontal flange plate 30, adjustably secured by the screws 31 to the flange 32, on the stationary holder plate 5. As indicated in Fig. I said plate 30 is so shaped as to provide supporting ledges 33 which respectively overhang the feed roller sections 34, which are loosely mounted for rotation, in spaced relation on the shaft 35, and have smooth resilient rubber faces.

As shown in Fig. III, the feed roller including sections 36, having corrugated resilient faces, rigidly mounted in spaced relation on the shaft 37, subjacent to the roller including the sections 34, and arranged to coöperate with and rotate the latter to feed the sheets 9 when engaged between them. It should be noted that, immediately after the wiping fingers have dislodged the forward portion of the end sheet and carried it downward into the bight of the feed rollers 36 and counter pressure rollers 34, the fingers return to engage the next to the bottom sheet while the major portion of the bottom sheet is still on the pile, being held above several of the rollers 13 under the pile of sheets. While this dislodged sheet is being fed by the rollers 36 and 34, the wipers are slowly acting on the next sheet. This simultaneous action enables great rapidity of delivery, while allowing a comparatively slow action of the wiping fingers.

The operation above described is effected by a train of gearing of which the initial member is the gear 40, which may be conveniently rotated in the direction of the arrow indicated thereon, by engagement with the gear of the printing machine with which the paper feeding device aforesaid is associated. Said gear 40 is rigidly connected with the driving shaft 41, which has a similar rigidly mounted gear 42, connected through the idler 43, with the gear 44 on the shaft 37, carrying the rigidly mounted feed roller sections 36, which, by their frictional peripheral contact rotate the feed roller sections 34, which are loosely mounted for independent rotation on the shaft 35. The driving shaft 41 is also provided with a gear 45 in mesh with the gear 46, which is loosely journaled on the shaft 35, but arranged to be intermittently connected to rotate said shaft by the pin 49 projecting from the gear 46, arranged to engage the arm 50, rigidly carried by said shaft 35. Said shaft 35 carries the fingers 51, which are formed of resilient rubber blocks, having notched or grooved faces secured in suitable slots in the hubs 52 rigidly secured to said shaft 35 by the set screws 53, and which are positively shifted in wiping con-

tact with the bottom sheet 9 of the stack 11 to draw back its forward edge from the supporting ledges 33. Said shaft 35 being further progressed at an accelerated speed independent of said gear 46, by the friction of the rollers 34 rotating thereon, which makes a plurality of rotations for each rotation of the wiping shaft. This shifts said fingers to the position shown in the drawings, out of the path of said sheet 9. As the end of the sheet is snapped down and caught between the opposite continuously rotated feed rollers 34 and 36, they withdraw it from beneath the stack and discharge it between the chute plates 7 and 6, to which it is directed by the guides 55, extending from the latter, as best shown in Fig. III.

I do not desire to limit myself to the precise details of construction and arrangement above described, as it is obvious that various modifications may be made therein without departing from the essential features of my invention, as defined in the appended claims. It should be noted, however, that this patent is subordinate to and dominated by my copending application No. 720,400, filed September 14th, 1912, which contains broad claims reading alike on the structure there shown and on the structure shown in the drawings of this patent. This patent is confined to mechanism not shown in said dominating application.

I claim:

1. In a paper feeding device, the combination with a holder for a stack of sheets; of an intermittently rotatable shaft mounted transversely beneath the forward end of said stack; an arm on said shaft; a series of feed roller sections loosely mounted on said shaft, and arranged for continuous rotation independently thereof; a continuously rotatable shaft carrying a roller arranged for peripheral contact with said loosely mounted rollers, to continuously rotate the latter; a series of fingers rigidly mounted on said intermittently rotatable shaft, arranged to engage the bottom sheet of said stack; whereby the forward edge of said bottom sheet is drawn back and snapped between said feed rollers and discharged from beneath said stack; a continuously rotatable gear loosely mounted on said intermittently rotatable shaft, having means arranged to intermittently engage said arm and thereby turn said intermittently rotatable shaft.

2. In a paper feeding device, the combination with a holder for a stack of sheets; of an intermittently rotated shaft extending transversely beneath the forward end of said stack; feed roller sections loosely mounted for independent rotation upon said shaft; a continuously rotated shaft, carrying a roller rigidly secured thereto, and arranged for peripheral engagement with said loosely

mounted rollers, arranged to rotate the latter continuously; fingers rigidly secured to said intermittently rotated shaft and having resilient faces arranged to engage the bottom sheet of said stack, which extends in tangential relation to the path of said fingers, whereby the forward edge of the bottom sheet of said stack is drawn back and snapped down between said feed rollers, and said sheet is discharged thereby; a gear loosely mounted on said intermittently rotated shaft and provided with a projection, an arm on said shaft arranged to be positively engaged by said projection when said fingers are in contact with said bottom sheet; said intermittently rotated shaft being rotated at an accelerated rate of speed to disengage said arm from said projection, and shift said fingers out of contact with said sheet by the frictional engagement of said rollers on said shaft.

3. In a paper feeding device, the combination with a holder for a stack of sheets; of an intermittently rotated shaft extending transversely beneath the forward end of said stack; a series of feed roller sections loosely mounted on said shaft and arranged to rotate independently thereof; a continuously rotated shaft extending parallel with said intermittently rotated shaft, and carrying a rigidly mounted roller in peripheral engagement with said loosely mounted roller, to continuously rotate the latter; a series of fingers rigidly mounted on said intermittently rotated shaft having resilient faces arranged to engage the bottom sheet of said stack which extends in tangential relation to the path of said fingers, and is shifted thereby to draw back its forward edge between said feed rollers, which engage said sheet and discharge it from beneath said stack; a gear loosely mounted on said intermittently rotated shaft and provided with a projection; an arm carried by said shaft extending into the path of said projection and arranged to be intermittently rotated thereby when said fingers are in contact with said bottom sheet, and rotated therefrom by the frictional engagement of the continuously rotated rollers mounted thereon which shift said fingers at an accelerated rate of speed out of the path of said sheet after they have drawn back the edge of said sheet; a gearing connection arranged to continuously rotate the feed roller shaft, and the gear on said intermittently rotated shaft.

4. In a paper feeding device, the combination with a holder for a stack of sheets; of an intermittently rotated shaft extending transversely beneath the forward end of said stack; a series of roller sections loosely mounted on said shaft and provided with smooth resilient rubber facings; a continuously rotated shaft extending parallel with said intermittently rotated shaft and pro-

vided with a rigidly mounted roller having corrugated resilient rubber facings arranged to peripherally engage said loosely mounted rollers, to rotate the latter continuously; a series of fingers carried by said intermittently rotated shaft, having notched resilient rubber facings arranged to engage the bottom sheet of said stack with a wiping contact, to draw back the forward end of said sheet and snap said edge down between said feed rollers which discharge said sheet from beneath said stack, said fingers being shifted out of the path of said sheet by the frictional contact of said rollers, which rotate at an accelerated rate of speed on said shaft; a gear loosely mounted on said intermittently rotated shaft and provided with a projection; an arm on said shaft, extending in the path of said projection, and arranged to be engaged thereby to positively rotate said shaft while said fingers engage said bottom sheet; and gearing connection arranged to continuously rotate said feed rollers and said gear.

5. In a paper feeding device, the combination with a holder for a stack of sheets; of a shaft extending beneath the forward end of said stack; a roller loosely mounted on said shaft; a finger carried by said shaft arranged to engage the bottom sheet of said stack and draw back the forward end of said sheet in a direction opposite to that in which it is desired to feed said sheet; another shaft extending parallel with said first named shaft and carrying a roller arranged to peripherally engage said loosely mounted roller; and means arranged to continuously rotate the last named shaft and intermittently rotate the first named shaft.

6. The combination of a shaft, a series of wiping fingers rigid thereon, a series of loose rollers between the fingers, a parallel shaft, a series of feed wheels rigid thereon coacting with the loose rollers, mechanism for giving said shafts continuous rotation in opposite directions, and means for supporting a block of paper in position to be acted on by the wiping fingers, whereby a sheet may be dislodged and thereby pass into the grasp of the feed rollers and their coöperating rollers.

7. The combination, with a series of rotary wiping fingers, of a roller parallel therewith, a series of ledges located between the paths of the fingers, said ledges and said roller being adapted to support the forward portion of a pile of paper, the wiping fingers acting to raise such portion and buckle the bottom sheet as they move toward said roller, loose rollers surrounding the shaft between the fingers, and feed rollers contacting with the loose rollers and mounting on an axis parallel therewith.

8. The combination of means for supporting a pile of paper, a shaft having a

wiping finger adapted to engage the sheets of said pile as the shaft is rotated, a feed roller, roller sections on the wiper shaft frictionally engaging the feed roller, driving means positively rotating the feed roller at a comparatively high speed, driving means adapted to shove the wipers around their axis at a comparatively slow speed, the connection between the last mentioned driving means and the wiper allowing independent movement of the latter, whereby, when the wiper clears the paper the friction with the interspersed rollers may turn the wiper at a comparatively rapid speed.

15 9. The combination of means for supporting a pile of paper, a series of rotary wiping fingers, means for giving them a slow

movement while in engagement with the bottom sheet of the pile and then a quick movement for the rest of the rotation, a paper-supporting roller parallel with the axis of the wiping fingers and at the rear thereof, a series of feed rollers below the axis of rotation of the wiping fingers, and counter rollers for the feed rollers mounted about 20 said axis and rotatable independently of the wiping fingers.

In testimony whereof, I have hereunto signed my name at Burlington, N. J., this 30th day of June 1909.

SAMUEL A. NEIDICH.
